PRESSURE DEVICE

Jean Mercier, New York, N.Y.

Application January 22, 1957, Serial No. 635,237

5 Claims. (Cl. 138—30)

In pressure accumulators of the type including a rigid container having a pair of ports at its respective ends with a deformable partition or bladder affixed to one of said ports and separating two fluids such as gas and liquid under pressure, if as the bladder expands to force liquid from the other of such ports, the wall of the bladder adjacent the free end thereof should contact the wall of the container before the portion of the bladder adjacent its affixed end, pockets may be formed filled with liquid which would not be expelled from the container. Thus, the accumulator would be inefficient in operation as only a portion of the liquid in the container would be utilized.

Where the bladder of a pressure accumulator serves to close the liquid outlet port when such bladder has expanded in the container to substantially its maximum amount, if such bladder in its inflated but undistended condition is of length substantially equal to that of the container, the liquid outlet port may be closed before substantially all of the liquid is expelled. If the bladder is considerably shorter than the container and upon expansion of the bladder, as fluid is forced from the container, when the major portion of the bladder wall engages the wall of the container, the free end of the bladder should be considerably spaced from the liquid outlet port, such free end would have to stretch excessively to reach the liquid port to close the latter, thereby subjecting the bladder to high stress with likelihood of rupture.

It is accordingly among the objects of the invention to provide a pressure accumulator of relatively low cost, which may readily be fabricated and which will function without likelihood of breakdown or rupture of the deformable bladder therein and with assurance that substantially all of the liquid will be expelled from the container.

Another object is to provide a bladder for a pressure accumulator of the above type which may readily be formed and which will provide for substantially complete expulsion of liquid from the accumulator container without likelihood of rupture of such bladder.

According to the invention, a partition or bladder is positioned in a rigid container to separate two fluids therein and is affixed in the container in such manner that the bladder defines two chambers for such fluids. The bladder is of greatest diameter adjacent the affixed portion thereof and the side wall of the bladder is substantially concave on its outer surface between the portion of greatest diameter and the free end of the bladder with all portions of the outer surface of the bladder between the greatest diameter portion and the free end being of diameter less than or substantially equal to a pressure portion.

This application is a continuation-in-part of copending application Serial No. 407,947, filed February 3, 1954, now Patent No. 2,786,488, March 26, 1957.

In the accompanying drawings in which are shown one or more of various possible embodiments of the several features of the invention,

2

Fig. 1 is a longitudinal sectional view of a pressure accumulator according to one embodiment of the invention, and

Fig. 2 is a view similar to Fig. 1 of another embodiment of the invention.

Referring now to Fig. 1 of the drawings, the pressure accumulator desirably comprises a container or pressure vessel 11, preferably of strong, rigid material such as steel, cast aluminum or the like, capable of withstanding high pressure and having a gas inlet port 12 and a liquid port 13 therein preferably opposed to each other. The container 11 may be spherical or cylindro-spherical as shown and has a partition therein between the gas and liquid ports, said partition illustratively being a collapsible and expandable bladder 14, desirably of resilient material such as rubber or synthetic plastic of like physical characteristics, which in distended but substantially unstretched condition is smaller than the cavity of the container 11 and has its longitudinal axis aligned with the ports 12 and 13.

As shown in Fig. 1, the bladder which is of length illustratively no less than three times its maximum diameter, has a rounded end 15 conforming to the curvature of the end 16 of the container 11 adjacent port 12 and is substantially in engagement therewith to the maximum diameter portion 17 of the bladder, and a portion 18 of the side wall of the bladder tapers inwardly from the maximum diameter portion 17 of said bladder. Thus the tapered portion 18 of the bladder is in the form of a frustum. The portion 19 of the bladder between the tapered portion 18 and the free end 21 thereof is substantially cylindrical in cross section extending substantially parallel to the wall of the container 11.

To minimize fatigue at the free end 21 of the bladder, such free end 21 has an outer width as at $a-a$ at the lower end 22 of the cylindrical portion 19 equal to a distance D, and the curvature of each of the side ends 23 of the bladder from the extremities of the line $a-a$ is a portion of the curve of a circle having a radius $1/4D$ taken along line $a-a$. The lower end 21 of the bladder has a curvature formed by a circle having a radius D with its axis along the longitudinal axis of the bladder.

As shown in Fig. 1, the thickness of the tapered portion 18 of the bladder wall gradually decreases from the larger diameter portion 17 thereof to the upper end 25 of the cylindrical portion 19 and the thickness of the cylindrical portion 19 gradually increases from its upper end 25 to its lower end 22.

The bladder 14 is rigidly affixed in the container 11 preferably by means of a fitting 31, which desirably has a substantially cylindrical stem portion 32 with a base disk presenting an outstanding lateral flange 33 at one end thereof, which desirably has an annular groove 34 in its upper surface 35 in which may be positioned the thickened rim 36 about the mouth of the bladder 14. Thus, when the parts are assembled as shown in Fig. 1, the bladder may be securely clamped in place by means of a nut 38 screwed upon the protruding threaded stem of the fitting, an annular shoulder 39 adjacent the root end of the stem abutting against the rim of the gas inlet port 12 to prevent cutting of the rim 36 of the bladder by excessive tightening of the nut.

Although the outlet port 13 of the accumulator could be controlled in any suitable manner, in the embodiment herein shown, it is preferred to use the general construction shown in United States Patent No. 2,469,171, dated May 3, 1949, by the use of which an outlet closure assembly 41 affixed in said port 13 may be removed without likelihood of injury to the mechanic. As shown in Fig. 1, this assembly desirably comprises a housing 42, preferably a tubular member which desirably has an external annular shoulder 43 at the upper end thereof

of outer diameter less than that of port 13. A locking member 44, illustratively a ring of greater outer diameter than said port 13 and deformable to permit its insertion thereinto, encompasses said tubular member and is seated on the rim 45 of port 13, the inner diameter of said ring 44 being less than the outer diameter of shoulder 43 so that said shoulder may seat on said rim. Encompassing said tubular member and in juxtaposition with said port 13 is a rubber gasket 46 which serves effectively to prevent leakage between the wall of port 13 and the outer wall of tubular member 42 when a nut 47 is screwed on the externally threaded portion 48 of said tubular member 32.

Desirably positioned in said tubular member 42 is a poppet valve comprising a valve head 51 adapted to seat on the beveled mouth 52 of tubular member 42 and having a stem 53 preferably formed integral therewith. Stem 53 is slidably mounted in bearing opening 54, desirably in a disk 56 mounted in the bore of tubular member 42, said disk having a plurality of openings 58 therethrough to permit the passage of fluid, said valve head being normally retained in open position by means of a coil spring 59 encompassing stem 53 between head 51 and disk 56. As the construction and operation of said outlet closure assembly per se forms no part of this invention it will not be further described.

The embodiment shown in Fig. 2 is substantially identical to that shown in Fig. 1 except for the construction of the bladder and corresponding parts have the same reference numerals primed.

As shown in Fig. 2, the bladder 14' which has a substantially constant wall thickness, has a rounded end 15' conforming to the curvature of the end 16' of the container 11' adjacent port 12' and is substantially in engagement therewith to the maximum diameter portion 17' of the bladder 14'.

The portion 61 of the side wall of the bladder between its maximum diameter portion 17' and its free end 21' is substantially conical in cross section, being concave on its outer surface with all portions of said side wall 61 between the greatest diameter portion 17' and the free end 21' being of diameter less than or substantially equal to a previous portion.

With the construction shown, when a valve (not shown) controlling the liquid outlet port 13, for example, is opened, the bladder will expand and elongate to force liquid from such outlet.

To avoid trapping of liquid between the bladder and the container, the bladder when expanding must progressively contact the container wall from the maximum diameter portion thereof to near the liquid port so that substantially all of the oil in the container will be forced from said port.

In addition, with a long bladder, i.e., when the length of bladder is at least three times its maximum diameter, it is essential that the lower end of the bladder be sufficiently close to the lower end of the container so that upon final expansion of the bladder to close the liquid port, the free end of the bladder will be sufficiently close to the lower end of the container to avoid excessive stretching of the bladder which might cause rupture thereof.

These results are accomplished by the constructions above described. Thus, as the rounded end 15 (Fig. 1) of the bladder conforms to the shape of the end 16 of the container 11 and is substantially against the latter, when the bladder starts to expand the end 15 will immediately press against end 16 so that rubbing is avoided and no liquid will be trapped.

As the region of the bladder adjacent the maximum diameter portion 17 is closest to the wall of the container, upon expansion of the bladder such region of portion 18 will first engage the wall of the container to force the liquid therebetween in a downward direction through outlet 13.

As the bladder expands further to force liquid from the container, both its length and diameter will increase. Inasmuch as each succeeding region of portion 18 of the wall of the bladder is further from such wall than the previous region, the wall of the bladder will progressively engage the container from its maximum diameter portion 17. The angle between the bladder wall and the container at each instant of contact desirably is substantially equal, illustratively in the order of five degrees, which is sufficient to provide sufficient distance not to trap liquid and the minimum angle for a long bladder of the dimensions above set forth. Thus, the portion of the bladder adjacent the point of contact thereof with the container never is parallel to the container.

When the thinnest region 25 of the bladder has engaged the wall of the container, as the portion 19 of the bladder is substantially parallel to the wall of the container and is of progressively increasing thickness, as it is sufficiently spaced from the container wall, the portion 19 will also progressively engage the wall of the container at a substantially constant angle at the moment of contact from the thinnest region 25 to the region 22 to preclude entrapment of liquid.

As the wall thickness of the portion 18 of the bladder progressively decreases from the maximum diameter portion 17 to the region 25, each succeeding region of such portion 18 will increase in length as set forth in co-pending application Serial No. 407,947, filed February 3, 1954, at a greater rate than the previous portion. Consequently, upon expansion and elongation of the bladder, the portion 19 of the bladder will move downwardly sufficiently so that the lower portion 22 of the bladder will only have to stretch a relatively small amount before the end 21 engages the valve head 51 to close the outlet port thereby avoiding stress on such lower portion which might cause rupture of the bladder and failure of the unit.

Thus, where the bladder is relatively long, i.e., of length greater than three times its maximum diameter and if it was conical in cross section along its entire length, the lower end thereof before expansion might be at such a great distance from the end of the container that rupture might occur. This is precluded with the construction above described.

In the embodiment shown in Fig. 2, as the wall portion 61 of the bladder is substantially concave approaching but not reaching parallel relation to the container, progressive engagement of the bladder with the container wall at a substantially constant angle at the moment of contact will also occur. Thus, entrapment of liquid is precluded.

In addition, as the lower end of the bladder will not be excessively spaced from the container wall even with a long bladder, such lower end will not have to stretch excessively to move in engagement with the container when the bladder is fully expanded.

With the constructions above described, entrapment of liquid due to the formation of pockets is substantially precluded with the resultant high efficiency in the operation of the accumulator due to the utilization of substantially all of the liquid in the container.

Furthermore, as the lower end of the bladder will be relatively close to the lower portion of the side wall of the container when the bladder has expanded, the portion of the bladder at its lower end will only have to stretch a relatively small amount before the outlet port is sealed thereby avoiding stress on such lower portion which might cause rupture of the bladder and failure of the unit.

As many changes could be made in the above constructions, and many apparently widely different embodiments of this invention could be made without departing from the scope of the claims, it is intended that all matter contained in the above description or shown in the accom-

panying drawings shall be interpreted as illustrative and not in a limiting sense.

Having thus described my invention, what I claim as new and desire to secure by Letters Patent of the United States is:

1. A bladder for a pressure accumulator comprising an elongated hollow member of resilient deformable material having a port at one end, said bladder being substantially conical in cross section adjacent the port end thereof and substantially cylindrical in cross section from the conical portion toward the free end of the bladder, said bladder being of maximum diameter at the extremity of the conical portion remote from the cylindrical portion.

2. The combination set forth in claim 1 in which the conical portion of the bladder wall is of progressively decreasing thickness and the cylindrical portion of the bladder wall is of progressively increasing thickness toward the free end of the bladder.

3. A bladder for a pressure accumulator comprising an elongated hollow member of resilient deformable material having a port at one end, said bladder having the outer surface of the side wall thereof concave at least along a portion of the length of the bladder and in the form of a curve which continuously approaches nearer to the longitudinal axis of the bladder but never reaches such longitudinal axis, said concave portion being of maximum diameter near the port end of the bladder.

4. The combination set forth in claim 3 in which the

5
10

length of the bladder is at least three times its maximum diameter.

5. A pressure accumulator comprising a rigid elongated hollow substantially cylindrical container having a pair of axially aligned ports, an elongated hollow bladder of resilient deformable material in said container having a port at one end affixed to one of the container ports, said bladder having the outer surface of the side wall thereof concave at least along a portion of the length of the bladder and in the form of a curve which continuously approaches nearer to the longitudinal axis of the bladder but never reaches such longitudinal axis, said concave portion being of maximum diameter near the port end of the bladder, said bladder when in substantially undistended condition having its longitudinal axis aligned with both of the ports of said container and having its side wall spaced from the container wall substantially the major portion of the length of said bladder.
